UNITED STATES PATENT OFFICE.

JORGEN P. L. JORGENSEN, OF OMAHA, NEBRASKA.

PORTABLE TURN-TABLE FOR AUTOMOBILES.

1,250,318.

Specification of Letters Patent. Patented Dec. 18, 1917.

Application filed July 5, 1917. Serial No. 178,639.

To all whom it may concern:

Be it known that I, JORGEN P. L. JORGENSEN, a citizen of the United States, residing at Omaha, in the county of Douglas and 5 State of Nebraska, have invented certain new and useful Improvements in Portable Turn-Tables for Automobiles, of which the following is a specification.

This invention relates to a portable turn-table particularly useful in garages, for 10 changing the position of automobiles where a floor space may be of limited area, and has for its object, broadly, to provide such a construction that vehicles may be readily 15 mounted upon or removed from the turn-table, and while mounted thereon may be swung to any desired position, the parts to be so arranged that they will be durable in wear and that all stresses may be adequately 20 sustained, and also that only a limited force will be required for operation.

The invention consists of the novel construction, combination and arrangement of parts as described herein and claimed, and 25 as illustrated in the accompanying drawing, it being understood that changes in size, form, proportion and minor details may be made within the scope of the appended claims.

30 In the drawing, Figure 1 is a partly broken, top plan view of the turntable. Fig. 2 is a bottom plan view of the same, the axle-levers being shifted to permit circular movements of the platform. Fig. 3 is a 35 view in longitudinal section on line 3—3 of Fig. 1. Fig. 4 is a transverse section between lines 4—4, Fig. 1. Fig. 5 is a detail showing a rock-lever. Figs. 6, 7 and 8 are enlarged detail views to clearly show the 40 mounting of the levers for a pull-and-push rod for controlling the shoes of the track-plates.

Referring now to the drawing which illustrates one embodiment of the invention, a 45 suitable platform is provided consisting of a pair of grooved plates or tracks 1, preferably constructed of channel iron, maintained substantially parallel by the pair of cross-plates 2. The platform is also provided, midway 50 between its ends, with a cross-plate 3, and with segmental tread-plates 4. While the plates 3 and 4 tend to reinforce the platform, they also perform other functions.

Each track-plate is provided on its lower 55 side with a pair of axle-levers 5, each hav-

ing a pivotal mounting midway between its ends upon a track-plate, as indicated at 6, and upon the outer end of each axle-lever, is mounted a wheel 7.

In order that the levers 5 may be simultaneously swung 45 degrees to the position shown in Fig. 2 to permit circular movements of the platform, certain mechanism is provided which is of simple construction, and may be conveniently operated by a single hand-lever 8 when applied to the crank-shaft 9, said shaft 9 being mounted in suitable bearings and supported by the frame or platform.

At 10 is indicated a draw-bar disposed 70 midway between the track-plates upon the upper sides of the cross-plates 2 between the outer ends of the segmental plates 4, said draw-bar being adapted to be reciprocated longitudinally by the rotatable movements 75 of the crank shaft 9, since a link 11 is pivotally connected at its respective ends with the crank-shaft and draw-bar, the latter, during its sliding movements, having bearings near its ends, upon the cross-plates 2, 80 the outer end-portions of the segmental plates 4 operating as guides for maintaining the draw-bar parallel with the track-plates.

Disposed below the cross-plate 3 and secured thereto by keepers 12 is a bracket 13, 85 and pivotally mounted as indicated at 14 (Fig. 5,) upon said bracket is a triangular rock-lever 15 provided with an arm *a* and a pair of opposed arms *b*, said rock-lever being adapted to be actuated by the movements of the draw-bar since a link 16 is pivotally connected at its respective ends with the arm *a* of said rock-lever and with the draw-bar.

Numerals 17 indicate a pair of actuating- 95 plates, these being disposed at the lower side of the platform and adapted to be simultaneously moved transversely thereof in directions opposed to each other below the track-plates 1, the cross-plates 3, and the segmental plates 4, by operation of the rock-lever 15, since each arm *b* of said rock-lever is provided with a link 18 pivotally mounted upon its end, the opposite ends of links 18 being pivotally mounted upon an actuating- 100 plate 17, as plainly shown in Fig. 2.

The simultaneous movements of the actuating-plates 17, thus described, will cause swinging movements, horizontally, of the axle-levers 5 since, as best shown in Fig. 2, 110

connecting-plates or links 19 are provided, each having a pivotal mounting for its respective ends upon an actuating-plate and an axle-lever.

5 The links, levers and draw-bar thus described are preferably of flat, attenuated form, so that while adapted to resist stresses to advantage, they may be disposed to occupy a limited space, for it will be appreciated that the track-plates should be disposed as near the ground or floor of a garage as possible for convenience in moving automobiles thereon; and the parts thus described are so adjusted that friction will be 15 scarcely appreciable when, by use of the hand-lever 8, the axle-levers 5 are swung, in either direction, approximately 45 degrees.

In order that the stresses directed to the actuating-plates 17 may be uniformly sustained, and that they may be maintained 20 parallel with the track-plates 1 during their simultaneous movements toward the middle or toward the sides of the platform, the pair of alining-plates 20 are provided, each being secured, as indicated at *c*, to an actuating-plate, said alining-plates, therefore, during operation, moving at right angles to the track-plates 1 in directions opposed to each other with their inner edges in engagement, while working in the guides or brackets 21, which are mounted on the outer sides of said track-plates.

On account of the construction as described, the movement of the axle-levers, as 35 to speed, will be uniform. As soon as a rotatable movement is imparted to the crank-shaft 9, a swinging movement will be communicated to all of the axle-levers, and a further rotatable movement of the crank-shaft will cause uniform swinging movements of the axle-levers regardless of depressions or obstructions which the wheels 7 may encounter, the completion of the 40 swinging movements in an arc of 45 degrees 45 for all of the wheels being coincident.

At the commencement of the swinging movements mentioned for the axle-levers, the actuating-plates 17 will be disposed at their nearest approach to each other, and the opposed axle-levers adjacent to the ends of the track-plates 1 will be in engagement with a cross-plate 2 which limits their movements in one direction, and they will be parallel as compared with each other; and when the 50 arc of movement of 45 degrees for said axle-levers has been completed they will be in engagement with the stop-members 22 provided by the ends of the cross-plates 2; and the pair of axle-levers of each track-plate 1 will 55 be then disposed at right-angles to each other, the actuating-plates being disposed at their greatest distance from each other.

As best shown in Fig. 1, the inner ends of the axle-levers are provided with small 60 wheels or rollers 23, adapted to engage the

upper sides of the segmental tread-plates 4, to maintain the axle-levers in a horizontal position, and it will be understood that by this construction the stresses occasioned by the weight of the load will be sustained by 70 the rollers 23 in conjunction with the wheels 7.

While the track-plates 1 are preferably curved longitudinally as shown in the drawing, this is not a necessary feature, but regardless of form and in order that the platform may be moved freely, the wheels, obviously, should have such a diameter that the track-plates will not engage the floor or base upon which the wheels are supported; 80 and therefore each track-plate is provided at each of its ends with an inclined shoe 24 adapted to be elevated or lowered, as may be required, the movements of said shoes to be simultaneous.

In the use of the shoes 24 they may lie upon the ground or other support to provide inclined treads for the wheels of an automobile so that the latter may be moved upwardly upon the track-plates at one end 90 of the platform, the shoes at the opposite ends of the track-plates engaging the ground or floor to temporarily prevent a rearward movement of the platform, this being a matter of convenience in operation.

In order that the shoes may be under control of an operator for elevating them from the floor so that the turntable may be moved, or may be swung downwardly to be pressed against the floor or ground, as mentioned, I 100 provide mechanism for coincidentally moving said shoes, consisting of an arrangement of pivotally connected rods, levers and links movable by a single operating-shaft 25 adapted to be rotated a limited distance in 105 either direction by use of a hand-lever 26, the arrangement of parts being substantially the same at both ends of the track-plates, as will be explained. Numerals 27 indicate coupling-rods which connect the pairs of 110 shoes at the respective adjacent ends of the track-plates.

As best shown in Figs. 2, 6 and 7, the operating-shaft 25 is provided with suitable bearings and is disposed transversely of, below and adjacent to one of the ends of the track-plates. It is adapted to cause swinging movements of levers 28 carried by said shaft, said levers 28 causing actuation of links 29 with which they are pivotally connected, as indicated at 30. Numerals 31 indicate a pair of levers having their inner ends pivotally connected with links 29, as indicated at 32, each lever 31 being fulcrumed to swing from a pivot 33 on the side of a 120 track-plate, the outer ends of levers 31 being pivotally connected with the sides of the shoes, as indicated at 34.

Numerals 35 indicate a pair of pull-and-push rods disposed parallel with the track- 130

plates, each having a mounting for one of its ends upon a pivot 30, adjacent to one end of a track-plate, its opposite end having a pivotal mounting indicated at 30' adjacent to the opposite end of a track-plate.

The pivots 30' also provide pivotal mountings for the links 28' and 29', the links 28' being pivotally mounted at d, as best shown in Fig. 8, and links 29' having pivotal connections 32' with the outwardly projecting levers 31' which are fulcrumed at 33', intermediate their respective ends, the outer ends of said levers 31' being pivotally mounted on the sides of the shoes, as indicated at 34'.

It will thus be seen that a rotatable movement of the operating-shaft in one direction will cause all of the shoes to move upwardly a limited distance, this being desired so that they will not prevent a free circular movement of the turntable; and the operating-shaft may be rotated in an opposite direction to cause the shoes to move downwardly for engagement with the floor, this being desirable when driving an automobile on the track-plates of the turntable.

In operation, the shoes, by a limited movement of the hand-lever 26 are moved to their lowermost position, the flat bottoms or sides of the shoes then resting on the floor or ground for adequately supporting the weight when engaged by the wheels at the time an automobile is driven upon the track-plates, the links 28 and 29 as well as links 28' and 29' being so disposed that they also resist stresses directed to the shoes.

By a reverse movement of the lever 26, an operator may then cause the shoes to be elevated, and by use of suitable handle-bars 36 the turntable together with its load may be moved forwardly or rearwardly, the axles 5 being at right angles to the track-plates and in engagement with cross-plates 2, which operate as stops.

By causing a rotatable movement of the crank-shaft 9, the axle-levers 5 may be swung 45 degrees for engagement with the stop-members 22, and the turntable then may be swung to a desired position, the line of movement for the wheels being a circle since the pivotal mountings 6 for the axle-levers are equi-distant from a common center, said center for this circular movement being the pivotal mounting 14 for the rock-lever 15, said pivotal mounting 14 being at the intermediate section of the longitudinal and transverse axes of the platform. On account of the last named features, the mechanism moved by the crank-shaft 9 will be attended by a limited degree of friction, and the stresses will be adequately sustained.

Numerals 37 indicate a pair of wings disposed adjacent to the sides of the track-plates and supported in the positions shown, by suitable brackets 38. They may be dispensed with in some instances but are con-

venient as side steps when leaving or entering an automobile mounted on the track-plates, the brackets 38 having an adequate length so that the wings or steps thus provided will be disposed a suitable distance 70 from the track-plates.

What I claim as my invention and desire to secure by Letters Patent is,—

1. In a portable turntable, a platform including a pair of substantially parallel track-plates, axles arranged in pairs, the axles of each pair being pivotally mounted between their ends on a track-plate equi-distant from a common center and provided with wheels, and means for moving the axles 80 in an arc substantially of 45 degrees.

2. In a portable turntable, a platform provided with stop-members and with second stop-members, axles arranged in pairs and provided with wheels, the axles of each pair 85 being pivotally mounted between their ends adjacent to a side of the platform, said axles normally being in engagement with the first named stop-members and being adapted to be moved in a circle's arc for engaging the 90 second stop-members, the pivotal mounting for the axles being equi-distant from a common center.

3. In a portable turntable, a platform provided with segmental trackways, a plurality of axles pivotally mounted on the platform midway between their ends, wheels journaled on the axles at one of their ends and disposed above the platform for engaging the segmental trackways, wheels journaled 95 on the opposite ends of the axles for engaging the ground, and means for moving the axles in a circle's arc with reference to the platform.

4. In a portable turntable for automobiles, 105 a platform, a pair of substantially parallel track-plates on the platform for supporting the wheels of an automobile, axles pivotally mounted between their ends and arranged in pairs, each pair projecting outwardly of the sides adjacent to the ends of the platform, wheels on the axles, said axles being adapted to be disposed substantially at right angles to the track-plates for moving the platform forwardly or rearwardly and 110 adapted to be moved in an arc substantially of 45 degrees for moving the platform circularly.

5. In a portable turntable, a platform provided with substantially parallel track-plates, a rotatable crank-shaft, pivotally mounted axles provided with wheels and normally disposed at right angles to the track-plates, and mechanism movable by the rotatable movements of the crank-shaft for 115 swinging the axles substantially 45 degrees horizontally from their normal position.

6. In a portable turntable, a platform provided with substantially parallel track-plates, a rotatable crank-shaft, a draw-bar 130

- movable by the rotatable movements of the crank-shaft, a rock-lever movable by the movements of the draw-bar, a pair of actuating-plates movable by the movements of the rock-lever, a pair of alining-plates movable by the movements of the actuating-plates, pivotally mounted axles provided with wheels and normally disposed at right-angles to the track-plates, said axles being adapted to have simultaneous movements in an arc substantially of 45 degrees with reference to the platform by the movements of the alining-plates.
7. In a portable turntable, a platform provided with parallel track-plates, shoes projecting beyond the ends of the track-plates, axles pivotally mounted between their ends on the platform and provided with wheels, means for simultaneously moving the axles horizontally in an arc substantially of 45 degrees, means for simultaneously elevating the shoes with reference to the track-plates, and means for simultaneously lowering the shoes with reference to the track-plates.
8. In a portable turntable, a platform provided with segmental trackways and a pair of track-plates, each track-plate having an outwardly-projecting shoe, a plurality of axles pivotally mounted on the platform midway between their ends, wheels journaled on the axles at one of the ends thereof and disposed above the segmental trackways for engagement therewith, wheels journaled on the opposite ends of the axles for engaging the ground, means for swinging the axles in an arc of 45 degrees with reference to the platform, means to elevate the shoes coincidently, and means to lower the shoes coincidently with reference to the track-plates.
9. In a portable turntable for automobiles, a platform, a pair of parallel track-plates on the platform for supporting the wheels of an automobile, each track-plate being provided with a shoe projecting beyond its end axles pivotally mounted between their ends and arranged in pairs, each pair projecting outwardly of the sides adjacent to the ends of the platform, wheels on the axles, said axles being adapted to be disposed at right-angles to the track-plates for moving the platform forwardly or rearwardly and adapted to be moved in an arc of 45 degrees for moving the platform circularly, a rotatable operating-shaft, and mechanism connecting the operating-shaft and shoes for elevating or lowering said shoes with reference to the track-plates by

the rotatable movements of said operating-shaft.

10. In a portable turntable, a platform provided with parallel track-plates, a rock-lever having a pivotal mounting upon and at the intersection of the longitudinal and transverse axes of the platform, a plurality of axle-levers each having a pivotal mounting equidistant from the pivotal mounting of the rock-lever, wheels disposed outwardly of the track-plates and mounted on the axle-levers, a crank-shaft, mechanism connecting the crank-shaft with the rock-lever, mechanism connecting the rock-lever with the axle-levers, said crank-shaft being rotatable for causing coincident swinging movements of the axle-levers in an arc of 45 degrees with reference to the track-plates.

11. In a portable turntable, a platform, a pair of parallel track-plates on the platform, each being provided with a shoe projecting beyond its terminal, a rock-lever having a pivotal mounting upon the platform midway between the track-plates, a plurality of axle-levers each having a pivotal mounting upon a track-plate equidistant from the pivotal mounting of the rock-lever, wheels on said axle-levers, a rotatable crank-shaft for actuating the rock-lever, mechanism movable by the rock-lever and connected with the axle-levers for causing coincident swinging movements of said axle-levers in an arc of 45 degrees, a rotatable operating-shaft, and mechanisms connecting the operating-shaft with the shoes for elevating or lowering said shoes with reference to the track-plates by the rotatable movements of said operating-shaft.

12. In a portable turntable, a platform, a pair of longitudinally grooved, parallel track-plates, a rock-lever having a pivotal mounting upon the platform, a plurality of axle-levers each having a pivotal mounting equidistant from the pivotal mounting of the rock-lever, wheels disposed outwardly of the track-plates and journaled on the axle-levers, means to actuate the rock-lever, and mechanism connecting the rock-lever and axle-levers, said mechanism being movable by actuation of the rock-lever for causing coincident swinging movements of the axle-levers in an arc of 45 degrees with reference to said track-plates.

In testimony whereof I have affixed my signature in presence of two witnesses.

JORGENSEN.
